Des. 222,671
Patented Nov. 30, 1971

222,671

AUTOMATIC PIPETTE

Alfred M. Blumenfeld, Jenkintown, Pa., assignor to
Micromedic Systems, Inc., Philadelphia, Pa.

Filed Nov. 16, 1970, Ser. No. 25,976

Term of patent 14 years

Int. Cl. D24—02

U.S. Cl. D16—2

FIG. 1

FIG. 2

FIG. 3

FIG. 4

FIG. 5

FIG. 1 is a front perspective view of an automatic pipette;

FIG. 2 is a front view thereof;

FIG. 3 is a rear view thereof;

FIG. 4 is a right side view thereof, the left side being identical; and

FIG. 5 is a top plan view.

I claim:

The ornamental design for an automatic pipette, substantially as shown and described.
